CARL GUSTAVE ROCH, OF PARIS, FRANCE.

GAS-REGULATOR FOR X-RAY TUBES.

1,182,709.

Specification of Letters Patent.

Patented May 9, 1916.

Application filed October 25, 1915. Serial No. 57,770.

To all whom it may concern:

Be it known that I, CARL GUSTAVE ROCH, medical student, resident at 31 Avenue d'Eylau, Paris, France, a citizen of the Republic of France, have invented new and useful Improvements in or Relating to Gas-Regulators for X-Ray Tubes, which improvements are fully set forth in the following specification.

10 This invention relates to an air regulator for X-ray bulbs and like apparatus. The regulator is without capillary tubes, with free mercury, and incapable of getting out of order. The regulator can work in any 15 position for the purpose of admitting small quantities of air or gas into the interior of X-ray bulbs, the admission being required from time to time for insuring good working of the bulbs.

20 Figure 1 is a vertical section of the apparatus, Fig. 2 shows a modified construction.

The apparatus chiefly comprises a spherical tank *s* filled two-thirds with mercury. Through the tank a tube *b* passes wide open 25 at both ends and establishing communication between the center *o* of the spherical tank and the atmosphere. A tube *a* is welded at a right-angle to the tube *b* at *o* and communicates with the end portion *a'* of the 30 tube *b*, and with the interior of the bulb *c* producing Roentgen rays.

The portion *a'* of the tube *a*, which is welded to the tube *b* and is slightly tapering, is filled with an exceedingly fine and compact porous material strongly adhering to the walls, preferably cast between the said walls so as to set in the interior; for the purpose of preventing any mercury from passing through the tube *a*, while remaining 35 permeable to the air. For this purpose, bone dust, or elder-tree-pith, or a porous cement made of loose grain, or porous porcelain, or wadding or other loosely-woven material may be used. The tube *b* is also provided 40 in its central portion with a widened chamber *b'* having the shape of a double cone and containing a compact plug which prevents mercury from passing, but is easily permeable to the air. This plug may be 45 made of any of the materials mentioned in connection with the plug used in the portion *a'* of tube *a*.

The tank *s* is provided on its circumference with openings or branches *s'*, of conical shape, arranged in such a number that, 50 whatever the position of the apparatus, at

least one of them is always above the surface of the mercury. These branches are closed by plugs, also of conical shape, as shown in the drawing, which prevent mercury from passing, but are also permeable to the air. These plugs are protected from any contamination from the outside by means of a membrane *m* (shown in dotted lines) which covers them and is secured by 55 a fine thread tied under the flange of the branch. In these conditions, assuming the apparatus to be at rest, the mercury, whatever be the position given to the apparatus, will always close the branch *a'* of the tube *a* 60 communicating with the bulb. If air or any gas is then introduced under pressure through the tube *b*, the mercury driven into the interior of the tank by the air-current coming from *b* in the direction of the 65 arrow, will uncover the branch *a'* of the tube *a*, so that a small quantity of air or gas will get into the bulb through the porous material contained in branch *a'*. If the volume 70 of air or gas driven through the tube *b* is too large, bubbles will escape through the end *o* and burst on the surface of the mercury, but the equilibrium between the inner 75 pressure of the tank *s* and the atmosphere will be at once reestablished through one of the branches *s'*, as at least one of the said 80 branches is always, as already stated, above the surface of the mercury. As soon as no more gas is blown in through the tube *b*, the mercury will at once return and fill the 85 tube *b* up to the plug *b'* and thus close the tube *a*.

Among other advantages, this apparatus offers: a constant and reliable tight joint, without any fear of the mercury overflowing 90 or of any cuts which are so dangerous and so frequent in regulators with capillary tubes; a great uniformity of working and of output, the mercury having at rest an invariable position of equilibrium; a perfect 100 working in any position, as the apparatus is absolutely symmetrical; and great ease in manipulation. With a simple rubber pear and a slight compression, a perfect working is obtained, even from a great distance. Violent blowing in through the tube *b* cannot 105 have any injurious effect, and the apparatus therefore can be used even by inexperienced operators.

In the modified construction shown in Fig. 2, the tube *b'* is shortened at its end *c* to an extent equal to the diameter of the

tube a' , so as to uncover completely the end a' of the porous material. Moreover, one of the branches s' , preferably that arranged in line with the tube a' , or a special branch, 5 is arranged to receive a cap h of metal or of any other material, provided with a screw-threaded branch. With the said branch engages a rod d , also screw-threaded, of iron or any other desired material, 10 terminating at one end in a widened portion which may or may not be covered with rubber. This rod finally terminates outside in a milled button e enabling it to be easily turned. The branch s' provided with this 15 device, is closed, like the others, by a plug which renders it permeable to the air, but not permeable to mercury.

The working of the modified constructions is as follows:—By screwing home the 20 rod d by means of its button e , the end a' of the porous material is completely closed. On the rod being slightly unscrewed, the end d will uncover the orifice a' , and, by regulating the distance separating the end d 25 from the branch a' , a more or less large quantity of air is admitted at will into the apparatus. The advantages of this arrangement are as follows:—Absolute safety at rest, in the event of accidental blowing in 30 of air through the tube b ; extremely accurate regulation of the output, enabling the regulator to be adapted to any pattern of apparatus and to any dimensions of tubes or valves.

35 Having now particularly described and ascertained the nature of my said invention and in what manner the same is to be performed, I declare that what I claim is:—

1. A gas regulator for X-ray tubes and 40 the like, capable of working in any position and comprising a spherical receptacle filled two-thirds full of mercury; a gas feed tube having its opening disposed approximately at the center of said receptacle, said tube 45 having a plug; a connecting tube leading from the source of X-rays to said receptacle, and likewise having its opening disposed approximately at the center of the latter and provided with a plug; and 50 branches or nipples on said receptacle pro-

vided with plugs, all of the various plugs being composed of a porous material which is impermeable to mercury but permeable to gas.

2. A gas regulator for X-ray tubes and 55 the like, capable of working in any position and comprising a spherical receptacle filled two-thirds full of mercury; a gas feed tube having its opening disposed approximately at the center of said receptacle, said tube 60 having a plug; a connecting tube leading from the source of X-rays to said receptacle, and likewise having its opening disposed approximately at the center of the latter and provided with a plug, the two 65 tubes arranged at a right angle to each other; an adjustable closure for the connecting tube; and branches or nipples on said receptacle provided with plugs, all of the various plugs being composed of a porous material which is impermeable to mercury but permeable to gas.

3. A gas regulator for X-ray tubes and 70 the like, capable of working in any position and comprising a spherical receptacle filled two-thirds full of mercury; a gas feed tube having its opening disposed approximately at the center of said receptacle, said tube 75 having a plug; a connecting tube leading from the source of X-rays to said receptacle, and likewise having its opening disposed approximately at the center of the latter and provided with a plug, the two 80 tubes arranged at a right angle to each other; an adjustable closure for the connecting tube; an operating rod for said closure having a finger-piece connected to it; and branches or nipples on said receptacle 85 provided with plugs, all of the various plugs being composed of a porous material which is impermeable to mercury but permeable to gas.

Dated this 29th day of September 1915.

In testimony whereof I have signed this specification in the presence of two subscribing witnesses.

CARL GUSTAVE ROCH.
